UNITED STATES PATENT OFFICE.

GEORGE JOHNSTON, OF DURBAN, SOUTH AFRICA.

CENTRAL BUFFER AND COUPLING.

SPECIFICATION forming part of Letters Patent No. 726,068, dated April 21, 1903.

Application filed November 14, 1902. Serial No. 131,425. (No model.)

To all whom it may concern:

Be it known that I, GEORGE JOHNSTON, a subject of the King of Great Britain, of Durban, South Africa, but at present residing in Liverpool, in the county of Lancaster, England, (whose full postal address is 65 Belmont road, Liverpool, aforesaid.) have invented certain new and useful Improvements in or in Connection with Central Buffers and Couplings, (for which application has been made in Great Britain, No. 18,784, dated August 26, 1902, and in Germany, filed September 4, 1902,) of which the following is a specification.

This invention relates to central buffers and couplings which will automatically couple up and in which coupling-hooks are used for engaging the draw-link.

It will be understood from the following description, reference being had to the accompanying drawings, in which—

Figure 1 is a sectional elevation of my buffers with one coupling-hook raised; Fig. 2, a plan; Fig. 3, an end view.

Referring to the figures, A is the central buffer, which is shaped as shown, and B the buffing or draw bar.

Mounted upon the horizontal pin C in the buffer A is a coupling-hook D, the claw d of which is an arc of a circle whose center is the pin C, and in proximity to the pin C the coupling-hook is formed with a box E, containing a sliding plunger G, at rear of which is a spring F, which normally keeps the plunger extended.

H is a cross-pin passing through a slot in the plunger, which limits the stroke of the latter.

I is a fixed abutment in the buffer, and the head of the plunger normally rests on this abutment, thus keeping the hook D raised in the position shown in Fig. 1. When, however, the plunger is pressed forward by the draw-link J of the opposing buffer striking against it on two vehicles coming together, it is disengaged from the abutment, allowing the coupling-hook to fall down through the link and through the orifice K in the buffer below the link. The head of the plunger G is so beveled as to admit of it being pressed back automatically by the abutment I when the coupling-hook is being raised. The coupling-hook can be raised by hand or by means

of a chain coupled to the link L, and when raised the plunger automatically springs up over the abutment I and forms a stop which 55 prevents the hook descending.

The buffers at each end of vehicle are made exactly similar, but one only in each pair is provided with a coupling-link. The buffer-head is made with a bell-mouth a and 60 a cavity wide enough to receive the coupling-link J. This cavity is preferably chamfered at the sides m, but made flat at bottom m'. The end of the link will therefore lie flat on this flat part m' of the buffer that is provided 65 with a coupling-link, and the weight of the coupling-hook pressing on the top of the coupling-link holds the link in a horizontal line, so that when two vehicles are brought together the coupling-link of one buffer will 70 approach the cavity M of the other buffer horizontally, and, furthermore, the mouth a of the buffer being chamfered or bell-mouthed insures the link entering it even if one buffer is on a lower plane than the adjacent buffer. 75

The dotted lines in Fig. 1 show the path in which the claw d of the coupling-hook travels. If desired, the coupling-hook can be held raised by being suspended by a chain coupled to the link L, and thus prevent the coupling-hook falling down. The coupling-hook could thus be retained in its raised position during shunting operations, so that vehicles will not automatically couple together. 80

The mode of action is as follows: When two 85 vehicles come together, the draw-link of one buffer automatically enters the mouth of the opposing central buffer and is guided by the chamfered sides into the exact position for the coupling-hook to fall, the draw-link J 90 pushing back the plunger G from engagement with the abutment I on the vehicles coming together. The coupling-hook at once falls by gravity through the link J, and thus fastens the buffers together. The shoulder 95 N coming against the rear of the buffer-head prevents the coupling-hook falling down too far. The moment, however, the coupling-hook is raised from the link J the chamfered head of the plunger G immediately it passes 100 the abutment I springs forward into position and rests on the abutment I on the buffer, thus preventing the coupling-hook from again falling into position until this or another link

is again inserted, when the weight of the coupling-hook on the pushing back of the plunger G by the link J causes the said coupling-hook to fall and lock the coupling-link.

5 I declare that what I claim is—

1. In automatic central buffers and couplings of that kind in which coupling-hooks are used for engaging draw-links, forming or providing the pivoted coupling-hook with a projecting hollow chamber or box, having a spring plunger or catch sliding therein, and the buffer with an abutment, said spring plunger or catch and the abutment being so combined and arranged that when the draw-link is pressed against the spring-plunger on two buffers coming together it will be pushed out of engagement with the abutment allowing the coupling-hook to fall down and engage the link, thus fastening the two buffers together, while the moment the two vehicles are separated and the coupling-hook is raised, the spring-plunger will reengage the abutment and prevent the coupling-hook from again falling down until the same or another link is reinserted, substantially as described.
- 25 2. A central buffer and coupling having a

coupling-hook for engaging the draw-link and a buffer-mouth for receiving the link in position for the claw of the hook to fall, in combination with a fixed abutment in the buffer, 30 and a bevel-headed sliding plunger or catch projecting from the boss of the coupling-hook, and kept normally extended by means of a spring, so as to engage on said abutment and hold the coupling-hook raised, said plunger 35 or catch being so arranged that on two vehicles coming together, the coupling-hook automatically pushes back the plunger clear of the abutment, leaving the hook free to fall through the link and fasten the two buffers 40 together, the beveled end admitting of the plunger freely passing the abutment when raising the coupling-hook again, substantially as described.

In witness whereof I have hereunto signed 45 my name, this 3d day of November, 1902, in the presence of two subscribing witnesses.

GEO. JOHNSTON.
